(57) **CLAIM**

The ornamental design for a strap connector, as shown and described.

DESCRIPTION

FIG. 1 is a front, top, and right side perspective view of a male component of a strap connector;

FIG. 2 is a rear, bottom, and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a rear, top, and left side perspective view of a female component of a strap connector;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is a front, top, and right side perspective view of a strap connector with the male component in a first rotational position relative to the female component;

FIG. 17 is a rear, bottom, and left side perspective view of the strap connector;

FIG. 18 is a top plan view thereof; and,

FIG. 19 is a top plan view of the strap connector with the male component in a second rotational position relative to the female component.
